DESIGN FOR A COMBINED IVY STAND AND BOWL

Samuel Cantor, Brooklyn, N. Y.

Application October 26, 1934, Serial No. 53,778

Term of patent 3½ years

To all whom it may concern:

Be it known that I, Samuel Cantor, a citizen of the United States, residing at Brooklyn, in the county of Kings and State of New York, have invented a new, original, and ornamental Design for a Combined Ivy Stand and Bowl, of which the following is a specification, reference being made to accompanying drawing, forming part thereof.

The dominant features of the design consist in the stand per se.

I claim:

The ornamental design for a combined ivy stand and bowl, substantially as shown and described.

SAMUEL CANTOR
